VENETIAN BLIND CONSTRUCTION

Harry S. Rosenbaum, Baltimore, Md., assignor to
The Eastern Venetian Blind Company, Baltimore, Md., a corporation of Maryland

Application July 27, 1951, Serial No. 238,802

11 Claims. (Cl. 160—173)

1

This invention relates to a cord and tape ladder fastener particularly adapted for fastening the lower ends of tape ladders and operating cords of Venetian blinds to the bottom rail of such blinds.

A Venetian blind ordinarily comprises a tilt bar, a bottom bar or rail, and pairs of vertical tapes depending from the tilt bar so that they face each other. The tapes extend downwardly the entire length of the blind and are fastened to the bottom bar or rail. Evenly spaced cross bars are provided between each pair of tapes to support the slats. These slats have holes therethrough adjacent the tapes to permit the passage of a blind raising cord which is fastened to the bottom rail and extends upwardly over pulleys usually positioned adjacent to the tilt bar. By rotating the tilt bar, the slats may likewise be tilted so as to maintain a substantially parallel relationship with the tilt bar and the bottom bar or rail.

Heretofore, it has been customary to secure the ends of the tapes permanently to the bottom rail as by drawing the ends of the tapes about the bottom rail and securing the ends thereto by means of tacks, screws or other means. In recent years, Venetian blinds have been constructed of metal slats and bottom rails, as distinguished from the previously used slats and rails formed of wood, thereby making it difficult to secure the ends of the tape ladders and the operating cords readily to the bottom rails in an inconspicuous manner which will permit quick attachment and detachment of these elements.

It is an object of the invention to provide means for attaching a cord and tape ladder to the upper surface of a bottom rail of a Venetian blind which means is concealed from view and does not mar the appearance of the blind.

It is another object of the present invention to provide a cord and tape ladder attaching means for a Venetian blind wherein the attaching means is formed as a detachable plate.

It is another object of the present invention to provide a cord and tape ladder attaching means for a Venetian blind wherein the plate includes a latch arrangement for securing the cord in position.

It is another object of the present invention to provide a cord and tape ladder attaching means wherein the plate further includes means for securing the tape thereto.

Other objects and the nature and advantages of the instant invention will be apparent from

2

the following description taken in conjunction with the accompanying drawings, wherein:

Fig. 1 is a side elevation showing the cord and tape ladder fastener attached to the bottom rail;

Fig. 2 is a top plan view of the device in attached position;

Fig. 3 is a top plan view of the device in the cord releasing position, with the device in the unit releasing position shown in dotted lines;

Fig. 4 is a section taken along the line 4—4 of Fig. 2;

Fig. 5 is a section taken along the line 5—5 of Fig. 2;

Fig. 6 is a view similar to Fig. 4 showing the device in process of being assembled to the bottom rail; and

Fig. 7 is a perspective view of the device removed from the bottom rail.

More specifically, according to the present invention, there is provided a longitudinal slot on the upper surface of the bottom rail at each point where the tape ladder and cord is to be attached thereto, and a device capable of securely but detachably gripping the lower end of the tape ladder and cord is inserted into the slot and securely but detachably fastened to the bottom rail.

In the drawing, the numeral 10 refers generally to a Venetian blind having a bottom rail 11 joined by vertical tapes 12 to a tilt rail (not shown). The vertical tapes 12 are joined by cross bars or members 13. As shown in Fig. 5, the bottom rail 11 is hollow and consists of an elongated strip of sheet metal bent to a substantially rectangular cross section by overlapping the longitudinal edges as at 14. The lapped surface is utilized as the lower surface thereof, and the upper surface is provided with a plurality of slots 15 in positions corresponding to the points at which the tape ladders are to be attached. As illustrated, the slots 15 extend longitudinally along the rail and are rectangular in shape. The upper and lower surfaces of the bottom rail can be shaped as rounded surfaces, as shown in the drawing, to provide a more pleasing appearance to the resulting blind.

The fastener device 16, illustrated in Fig. 7, comprises a curved surface 17 curved in an arc corresponding to the curve of the upper surface of the bottom rail. Opposite lateral edges 18, 19 of the curved surface are bent downwardly at 90° to form flanges 18', 19'. The central portion of flange 18' has an extension 20 integral therewith that is bent outwardly to a

substantially horizontal position. The width of extension 20 is somewhat less than the width of slot 15 in the bottom rail so that extension 20 can be readily inserted therein. A bayonet slot 21 is provided in flange 18' at each side of extension 20, for a purpose to be described hereafter.

The curved surface 17 is provided with a cord opening 22 therein that is relatively wide at the outer end adjacent to edge 18 and relatively narrow at the inner end adjacent to the center of the curved surface 17. The wider opening is sufficiently wide to permit passage of the knotted end of the cord, whereas the narrow opening is merely wide enough to permit passage of the cord itself but not the knotted end thereof. Adjacent to the outer end of cord opening 22, a portion of curved surface 17 is bent upwardly and then flattened as at 23 to form a catch 24. The catch 24 is located adjacent to the flange 18' and has a width approximately the same as extension 20.

Flange 19' is cut away at the central portion 25 and is adapted to receive a latch assembly 26 therein. The latch assembly 26 is hinged to the surface 17 adjacent to the flange 19' so that the entire latch assembly 26 can be swung upwardly about the hinge to the position shown in Fig. 7 and downwardly to the operative position adjacent to the surface 17. The latch assembly 26 comprises a hinge portion 27 and a latch portion 28 which are pivotally attached to one another to permit horizontal rotation of the latch portion 28 with respect to the hinge portion 27. The hinge portion 27 includes a pair of loops 29 adapted to pass through small openings 30 in the curved surface 17 adjacent to the flange 19' to provide the hinge. An extension 31 extends outwardly from the hinged section, and a flat portion 32 extends inwardly. The latch portion 28 is pivotally attached to the flat portion 32. The latch portion 28 is in the general shape of a semi-circle having a cutaway portion 33 at the center thereof. A knob 34 is provided along a portion of the circumference thereof for use in actuating the latch. When the latch assembly 26 is in its operative position, flat against the curved surface 17 as shown in Figs. 4 and 5, the outer surface of the latch portion 28 passes under the catch 24 and is retained therein. In this position, the cutaway portion 33 of the latch is in alignment with the narrower inner portion of the cord opening 22 with the wider outer portion of the cord opening covered so that the resulting opening near the center of the curved portion 17 has a diameter approximately equal to the diameter of the cord. The extension 31 on the latch assembly extending outwardly therefrom is of a width slightly less than the width of the slot 15 in the bottom rail and is adapted to pass through the slot 15. When the extension 31 is swung downwardly about hinge loops 29 until in a vertical position, extension 20, at the opposite end of the device, can then be inserted into the slot 15, as shown in Fig. 6, and the entire device swung downwardly until extension 31 has passed into the slot 15 at the opposite side thereof. The catch assembly is then swung downwardly to the curved portion 17, at the same time rotating extension 31 to a horizontal position beneath the curved portion 17 to prevent its removal therefrom.

A U-shaped member 35 has a pair of legs 36, 37 somewhat longer than the width of the vertical tape and a connecting portion 38 having a

width slightly greater than the cutaway portion 25 in flange 18'. The connecting portion 38 passes through the loops 29 beneath curved surface 17 and is thus rotatably hinged with respect to both curved surface 17 and latch assembly 26. The legs 36 and 37 are adapted to extend across beneath curved surface 17 and pass into bayonet slots 21 to retain the U-shaped member in locked position. The U-shaped member 35 is preferably made of thin material so that the outer ends of the legs 36, 37 are resilient and engage the bayonet slots tightly.

The method of assembling and utilizing this device will now be described. Loops are provided 15 at the lower end of each vertical tape 12 by folding back a portion of the tape and sewing, stapling or otherwise securing it. The U-shaped member is released from the bayonet slots and 20 then flattened as at 23 to form a catch 24. The catch 24 is located adjacent to the flange 18' and has a width approximately the same as extension 20. The loop at the end of each vertical tape is inserted over a leg of the U-shaped member and the ends of the legs are inserted into the bayonet slots, thus 25 securing the ends of tape ladder to the fastener device with the ladder extending upwardly therefrom. The latch assembly is next swung upwardly to the position shown in Fig. 7. Extension 31 is now inserted into one side of the slot 15 in the bottom rail as shown in Fig. 6. The entire fastener device is then swung downwardly 30 toward the bottom rail with the extension 31 entering the slot 15. At this point, the latch assembly is swung downwardly to curved portion 17, thus swinging extension 31 into the hollow portion of the bottom rail beneath the upper surface thereof. The knotted end of the cord can 35 now be inserted into cord opening 22 at the wider portion and the cord moved over to the narrow portion thereof. The latch portion 28 is now rotated until the end thereof passes beneath the catch 24 to a fully locked position. In this position, the operating cord cannot be removed since the knot at the end thereof will not pass through the resulting narrow cord opening. The fastener device is retained rigidly against the top surface 40 of the bottom rail by the two extensions thereon. The ends of the tape ladders are engaged beneath the curved surface 17 within the bottom rail by the U-shaped member, with the vertical tapes 45 passing out and upwardly at opposite sides of the device.

The tape ladders passing along opposite sides of the device tend to conceal the device so that although it is readily accessible, it is unseen and does not mar the appearance of the blind.

When it is desired to remove the operating cord alone, so that individual slats can be removed without removing the tape ladders, the latch portion is swung horizontally about its vertical pivot axis to the cord releasing position 55 shown in dotted lines in Fig. 3, in which position the end of the latch portion is still retained by the catch, however, the wider portion of the cord opening in the surface 17 is exposed, thus permitting removal of the knotted end of the cord. The fastener device, however, is still locked 60 within the bottom rail.

If it is desired to remove the tape ladder and the bottom rail, the latch portion is swung horizontally about its vertical axis beyond the catch member, and then upwardly about its horizontal hinge until extension 31 on the device is in a vertical position and can be lifted from the slot 65 in the bottom rail. This releases the bottom rail. By releasing the U-shaped member legs from the bayonet slots and swinging the mem-

ber about its hinge, the tape ladder ends can be removed from the legs and released.

It is apparent that the present invention provides a fastener for Venetian blind tape ladders and operating cords that permits the ready assembly of the tape ladders and cords to the bottom rail without the use of tacks or other securing devices, and in which the tapes are at all times free to be removed and adjusted as necessary during the assembly operation. The completed assembly can be readily removed entirely, or if desired, the operating cord alone can be removed without removing the balance of the assembly.

It will be obvious to those skilled in the art that various changes may be made without departing from the spirit of the invention and therefore the invention is not limited to what is shown in the drawings and described in the specification but only as indicated in the appended claims.

What is claimed is:

1. In a Venetian blind having a bottom rail and employing a tape ladder and an operating cord, said bottom rail having a slot in the upper surface thereof, a plate adapted to be disposed transversely across the upper surface of said bottom rail, said plate having a width corresponding to the length of said bottom rail slot, an extension integral with said plate and extending outwardly therefrom horizontally in a plane lower than the upper surface of said plate, said extension being slightly narrower than the width of said bottom rail slot, a member pivotally attached to said plate and having a portion extending outwardly therefrom in a direction opposite to said first extension in a plane lower than the upper surface of said plate, said member being capable of rotation from a vertical to a horizontal position while said plate is in a horizontal position, whereby said plate can be attached to the upper surface of said bottom rail by inserting said extension into said bottom rail slot below said upper surface of the plate and moving said second member from a vertical to a horizontal position with the extending portion below said upper surface of the plate.

2. In a device in accordance with claim 1, wherein said plate has a cord opening therein wide enough at one end to permit passage of the knotted end of said operating cord, and narrow enough at the other end to permit passage of the cord itself but not the knot thereon, and means for closing the wide end of said opening so that only the narrow end of said opening remains open, whereby removal of the knotted end of said cord is prevented when the closure means have been actuated.

3. In a device in accordance with claim 1, including means for locking said member into its horizontal position thereby preventing removal of said plate from said bottom rail.

4. In a device in accordance with claim 3, wherein said plate has a cord opening therein wide enough at one end to permit passage of the knotted end of said operating cord, and narrow enough at the other end to permit passage of the cord itself but not the knot thereon, and means for closing the wide end of said opening so that only the narrow end of said opening remains open, whereby removal of the knotted end of said cord is prevented when the closure means have been actuated.

5. In a device in accordance with claim 1, said plate having a cord opening therein wide enough

at one end to permit passage of the knotted end of said operating cord, and narrow enough at the other end to permit passage of the cord itself but not the knot thereon, a catch on the upper surface of said plate, a latch pivotally attached to said member about a vertical axis when the member is in its horizontal position, said latch being adapted to be rotated to a locked position wherein the latch is retained by said catch and closes the wide end of said cord opening.

6. In a device in accordance with claim 1, including a U-shaped member rotatably attached to said plate in such a manner that the legs of said member are free to rotate with respect to said plate beneath the upper surface thereof, each said leg being adapted to engage the lower end of one vertical tape of said tape ladder to fasten the end of said tape ladder to said bottom rail, and the portion connecting the legs of said U-shaped member acting as the pin for pivotally attaching said member to said plate.

7. In a device in accordance with claim 1, said plate having a cord opening therein wide enough at one end to permit passage of the knotted end of said operating cord, and narrow enough at the other end to permit passage of the cord itself but not the knot thereon, a catch on the upper surface of said plate, a latch pivotally attached to said member about a vertical axis when the member is in its horizontal position, said latch being adapted to be rotated to a locked position wherein the latch is retained by said catch and closes the wide end of said cord opening, said latch being so shaped that it may be rotated from a position wherein it is retained by said catch and the wide portion of said cord opening is closed, to an intermediate position wherein it is still retained by said catch but the wide portion of said cord opening is not closed, and to an unlocked position wherein it is not retained by said latch and the wide portion of said cord opening is not closed.

8. In a Venetian blind having a bottom rail with a slot formed in the upper surface thereof, a plate disposed transversely across the upper surface of said bottom rail and retained thereon, said plate having an operating cord opening formed therein with a wide and narrow end, a latch assembly hinged to said plate, said latch assembly including a hinge portion having an extension integrally formed therewith in a plane lower than the upper surface of said plate, said extension adapted to extend into said slot for securing said plate on said bottom rail, and a latch portion pivotally secured to said hinge portion and adapted to be rotated over the upper surface of said plate to cover the wide end of said cord opening thereby retaining the knotted end of said cord beneath said plate.

9. In a Venetian blind as set forth in claim 8, a U-shaped member pivotally secured to the lower surface of said plate in such a manner that the legs of said member are free to rotate with respect to said plate, each of said legs engaging the lower end of a tape ladder thereby fastening said tape ladder to said bottom rail and the portion connecting the legs of said U-shaped member acting as the pin for attaching said hinge portion to said plate.

10. In a Venetian blind as set forth in claim 9, wherein said plate has a pair of bayonet slots formed therein for receiving the free ends of said legs, thereby locking said U-shaped member in position against said plate.

11. In a Venetian blind having a bottom rail, a plate adapted to be secured to said bottom rail, said plate having an opening formed therein with a wide end and a narrow end, extension means formed integral with said plate adjacent said opening and extending outwardly from said plate in a plane lower than the upper surface of said plate to engage said bottom rail, latch means pivotally secured to said plate on the end opposite said extension means, said latch means including hinge means having a second extension formed integral therewith extending outwardly therefrom in a plane lower than the upper surface of said plate, said hinge means adapted to be moved from a vertical to a horizontal position thereby moving said second extension into engagement with said bottom rail, and a latch pivotally secured to said hinge means and adapted to be

moved over said wide end of said opening when said plate is positioned on said bottom rail.
